UNITED STATES PATENT OFFICE.

LINUS YALE, OF NEWPORT, NEW YORK.

BANK-LOCK.

Specification of Letters Patent No. 12,932, dated May 22, 1855.

To all whom it may concern:

Be it known that I, LINUS YALE, of Newport, in the county of Herkimer and State of New York, have invented a new and Improved Lock for Fireproof Safe, Bank-Vault, and other Doors; and I do hereby declare that the following is a full, clear, and exact description of the same, reference being had to the annexed drawings, making 10 a part of this specification, in which—

Figure 1 is an external view of my improved lock. Fig. 2 is an internal view of ditto, the casing nearest the eye being removed, and the lock represented in a locked state. Fig. 3 is also an internal view of ditto, the lock being represented in an unlocked state. Fig. 4 is a horizontal section of the working parts of ditto, the casing of the lock not being shown, (x) (x) Fig. 3 15 is the line of section. Fig. 5 is a transverse vertical section of ditto, (y) (y) Figs. 1 and 2, being the line of section. Fig. 6 is 20 also a transverse vertical section of ditto, (z) (z) Figs. 1 and 3, being the line of section.

Similar letters of reference indicate corresponding parts in the several figures.

The nature of my invention consists in the employment of a sliding plate and frame 30 constructed, arranged, and operating in connection with pins or rods and a key of peculiar construction as will be presently shown and described.

To enable others skilled in the art to fully 35 understand and construct my invention, I will proceed to describe it.

A, represents the casing of the lock, and B, is the bolt which slides or works between proper stumps (a) in the usual way.

40 The back end of the bolt B, has a recess or rebate (b) cut in it leaving a shoulder (c) at one side, and a ledge (d) at the back end of the bolt, between the shoulder (c) and the ledge (d) a frame C, is fitted. The 45 side of this frame adjoining the shoulder (c) of the bolt has a series of holes made through it, and a corresponding number of holes are made into the shoulder (c) and rods (e) (e') are fitted in these 50 holes, two rods in each hole, the rods (e) in the holes in the shoulder (c) bearing against spiral springs (f), see dotted lines Figs. 2, 3, and 4. The rods (e) in the shoulder (c) are of equal length, but the 55 rods (e') in the side of the frame C, are of

unequal length, and the rods (e) project into the holes in the side of the frame C, and prevent said frame from being moved upward in the bolt when the lock is in a locked state as will be presently shown.

60

In the frame C, there is fitted a sliding plate D, which has a curved or segment recess (g) cut in it, and holes are cut through the edge of the plate D, into the recess (g) in which holes the ends of the rods (e') 65 pass, and project into the recess at unequal distances, as the rods (e') as before stated are of unequal lengths. The plate D, has also an oblong slot (h) cut through it in which the bit (i) of the knob E, fits, see 70 Figs. 2, 3, and 4.

The knob is provided with a circular plate (j) at its inner end, said plate fitting in a circular recess in the inner surface of one side of the casing, as shown in Figs. 75 4, 5, and 6. The bit (i) is attached to this plate, as shown in Fig. 4. The knob also has an oblique opening (k) which passes longitudinally through it as shown clearly in Fig. 6. The plate D, slides laterally 80 a certain distance in the frame C, a ledge (l) on the under side of the plate strikes against the side (m) of the frame C, opposite the side in which the rods (e') are fitted, and determines the length of the vibration of the plate. Through the front 85 side of the casing there is made a rectangular opening E', see Figs. 1, and 5.

F, is the key of segment form corresponding to the recess (g) in the plate D, the 90 key has a series of holes (n) of different depths in one of its sides, see Figs. 5 and 6.

Suppose the lock to be in a locked state as shown in Fig. 2. It will be seen that the plate D and frame C are depressed or moved 95 down and its back end bears against the stump (a) and prevents the bolt B, from being thrown back. The plate D, and frame C therefore must first be raised. The key F, is inserted in the opening E', and passes 100 down into the recess (g) in the plate D, the holes (n) in the side of the key being opposite the rods (e'). The depths of the holes (n) vary as before stated and correspond to the difference in length of the 105 rods (e'). The key being within the recess (g) the knob E, is turned from left to right and the bit (i) first moves the plate D, toward the shoulder (c) and the key F, is pressed against the ends of the rods 110

(e') which pass into the holes (n) of the key F, and the key forces the rods (e) in the shoulder (c) till their ends are flush with the inner surface of the shoulder. The 5 plate D, and frame C may now be raised as the rods (e) are free from the holes in the side of the frame C, and the bit (i) acts upon the upper edge of the slot (h) in the plate D, and moves said plate up-
10 ward free from the stump (a) and the bit (i) then acts against the side of the slot and throws the bolt back as the ledge (l) acts against the side (m) of the frame C, and the side (m) against the ledge (d) at
15 the back end of the bolt B. When the bolt B, is thrown back the recess (g) is in line with the oblique opening (k) in the knob E', and the key will pass out of the recess (g) and through the opening (k) into the
20 hand.
In locking the lock no key is required, the knob being merely turned in an opposite direction and the plate D, being moved back to its original position as shown in
25 Fig. 2.
The advantages of the above lock are, that it cannot be picked as the recess (g) is thrown beyond the opening E', in the casing before the bolt can be thrown back so that
30 there is no opportunity for a burglar to tamper with the lock, or take impressions in wax to form a key. There is not sufficient space allowed to receive a requisite quantity of powder to blow off the lock. The key
35 is convenient to carry in the pocket, and the

construction of the lock is extremely simple and economical to manufacture.

I do not claim separately the rods (e) (e') working in holes in the bolt B, and a sliding frame C, for that is an extremely 40 old fastening and used in locks many years since, but

What I claim and desire to secure by Letters Patent, is,

1. The sliding frame C, and plate D, in 45 combination with the rods (e) (e') when constructed and arranged as herein shown, so that the plate D, will during the operation of unlocking the lock cover the opening or keyhole E', in the casing before the bolt 50 can be thrown back, thereby preventing the lock from being picked or impressions taken to form a key.

2. I also claim unlocking the lock by means of a segment key F, which is placed 55 within a corresponding shaped recess (g) in the plate D, by passing said key through the opening or key hole E', and moved with said plate so that when the bolt B, is thrown back the recess (g) and key F, will be in 60 line with or opposite to the opening (k) in the knob E, thereby allowing the key to pass out of the recess (g) through said opening (k) into the hand as herein shown and described.

LINUS YALE.
